SURGICAL SCISSORS

Richard E. Ericson, 127 E. Main St., Barrington, Ill.

Filed May 8, 1963, Ser. No. 74,809

Term of patent 14 years

(Cl. D83—12)

Fig. 1.

Fig. 2.

Fig. 3.

FIGURE 1 is a side elevation of a surgical scissors showing my new design with the jaw members in partially open position;

FIGURE 2 is an elevation as seen from the opposite side of FIGURE 1, with the jaw members in closed position;

FIGURE 3 is a front elevation thereof.

I claim:

The ornamental design for surgical scissors, substantially as shown.
